ATTORNEY

UNITED STATES PATENT OFFICE.

IRVING BLOUNT, OF NEW YORK, N. Y.

SEPARATOR.

1,063,322.

Specification of Letters Patent. Patented June 3, 1913.

Application filed January 19, 1912. Serial No. 672,051.

To all whom it may concern:

Be it known that I, IRVING BLOUNT, a citizen of the United States, and a resident of the borough of Brooklyn, city and State 5 of New York, have invented certain new and useful Improvements in Separators, of which the following is a specification.

This invention relates to apparatus for separating liquids from solids, and more 10 particularly to apparatus for separating oils, grease, water, etc., from garbage or other matter, and is a specific form of the invention described in my Patent No. 1,016,241, granted January 30, 1912.

15 One of the objects of my present invention is to provide an apparatus of the kind stated, the container of which is composed of a plurality of sections secured in endwise relation and so arranged that one or both 20 end sections may be disconnected from the middle section, removed therefrom and turned to a position to discharge the matter contained therein.

Other objects will appear from the here- 25 inafter description.

One embodiment of this particular form of the invention is illustrated in the accompanying drawing, in which the figure there shown is a longitudinal section of the apparatus illustrating in full lines one of the end sections disconnected from the middle section and at a distance therefrom. The dotted line position shows this section turned for discharging the contents thereof.

35 The apparatus here shown is composed of three sections marked A, B and C, respectively. The section A is fixed, and B and C are removably secured to the opposite ends of said section A. Each of these sections B and C is formed of an outer wall 12, and an inner wall 13, spaced from each other by a spacing and stiffening member 14. The central section A, is preferably of cylindrical form, and each end section is 40 preferably in the form of a frustum of a whole cone. The central section A is provided with a hopper or other suitable means, D, through which the material to be treated is charged to the container. This hopper 45 has a valve E for controlling the passage of the material therethrough. Steam or other suitable means for extracting purposes is introduced through the pipe G. In operation, the sections A, B and C are relatively 50 arranged to form a chamber into which the material to be treated is supplied through

the hopper D. When this chamber has received the required amount of material, the valve E is closed and steam or other suitable fluid is introduced through the pipe G. 60 This fluid may be under sufficient pressure to compact the solid residue of the material. The extracted liquid and the extracting fluid employed flow through the perforated inner walls 13 of the sections A, B and C, 65 and into the space between said walls and the outer wall 12, and ultimately reach the space or chamber 16, between the inner and outer walls of the section A, and collect at the bottom of the latter, the bracing members 14, being interrupted wherever necessary to permit the fluid to freely flow to the chamber 16. The chamber 16 is provided with one or more outlets for the discharge of the extracted fluid therefrom. 70

75 During the extracting process the sections B and C are rigidly clamped to the ends of the section A, by suitable means, such for example, as the bolts 18 pivoted to the flanges 19 surrounding the ends of the section A, and extending through apertures in said flanges, and the apertures in the flanges 20 on the inner end of each of the sections B and C. When the liquid matter has been extracted the bolts 18 are released and the 80 end sections are disconnected from the middle section and then tilted so that the open end will be downward, so that the solid matter contained therein may be readily and freely discharged therefrom. This dis- 85 charge may be effected by gravity, but it is preferable to assist gravity by means of pressure. An example of a pressure supply means for this purpose is a pipe H connected to the closed end of said removable sections, 90 through which a suitable source of fluid, under pressure, such as air or steam, may be forced to drive out the contents of the said movable sections. The said movable sections are provided with hoisting or dump- 95 ing apparatus of a suitable kind. Preferably, this apparatus consists of a bail 30, so pivoted at 31, to the sections B and C, that when removed from the middle section, said section hangs so that the discharge end 100 thereof is slightly in an upward position, as the section B shown in full lines in the figure. To the bail is connected a hoisting apparatus 32, the upper end of which is connected to a trolley 33, movable on a track 34. 110 To the closed end of each of the movable sections at 35, is connected one end of a

wire or rope 36, the other end of said rope passing through a block 37, secured to the trolley. This rope is for the purpose of raising the closed end of each movable section and swinging the same on its pivot 31, so that the open end will be downward for discharging the contents thereof, as shown in dotted lines in the figure.

Having now described my invention, what I claim as new and desire to secure by Letters Patent is:

1. In an apparatus of the kind described, a container having an inner and an outer wall, with a space between the inner wall being adapted to retain solid matter and to permit liquid to pass into said space, said container having end sections secured thereto and adapted to be removed therefrom, means for suspending said end sections when removed from the middle section, and means to turn said end sections into a downwardly open position for the discharge of the solid matter contained therein.

2. In an apparatus of the kind described, a container comprising a fixed section and a section removably secured thereto and adapted to be disconnected therefrom, means for suspending the removable section when removed from the fixed section and means to turn the removable section to a downwardly open position for the discharge of solid matter therefrom, each of said sections having inner and outer walls with a space between, the inner walls being adapted to permit liquid to pass into said space and to retain solid matter, and means through which the container is supplied with material to be treated and with a fluid for extracting said material.

40 3. An apparatus of the kind described,

having a treating chamber consisting of a stationary middle section and two connected end sections adapted to be disconnected from said middle section, means for suspending the removable end sections and means for limiting the swing of said sections and moving them into downwardly open position for the discharge of solid matter therefrom.

45 4. An apparatus of the class described, consisting of a stationary section and a removable section connected thereto, means for suspending the removable section so that its open end will be upward when removed from the stationary section, and means for removing the said section from the stationary section.

50 5. An apparatus of the class described, consisting of a stationary section and a removable section connected thereto, means for suspending the removable section so that its open end will be upward when removed from the stationary section, and means connected to the removable section for swinging it on its pivot to turn the open end downward for discharge.

55 6. An apparatus of the class described consisting of a stationary section and a removable section connected thereto, means for suspending the removable section when disconnected from the stationary section, and means for limiting the swing or tilting of the removable section.

60 In witness whereof I have hereunto set my hand at the city and State of New York, this 29th day of December, 1911.

IRVING BLOUNT.

In presence of—

ISABEL R. RICHARDS,
JOHN J. RANAGAN.
